UNITED STATES PATENT OFFICE.

THOMAS F. BANIGAN, OF KENVIL, NEW JERSEY, ASSIGNOR TO HERCULES POWDER COMPANY, OF WILMINGTON, DELAWARE, A CORPORATION OF DELAWARE.

PROCESS FOR PRODUCING NITRIC ACID.

1,332,195.

Specification of Letters Patent.

Patented Mar. 2, 1920.

Original application filed August 22, 1918, Serial No. 250,978. Divided and this application filed March 12, 1919. Serial No. 282,205.

To all whom it may concern:

Be it known that I, THOMAS F. BANIGAN, a citizen of the United States, residing at Kenvil, county of Morris, and State of New Jersey, have invented a new and useful Improvement in Processes for Producing Nitric Acid, of which the following is a full, clear, and exact description, reference being had to the accompanying drawings, which form a part of this specification.

While a careful study of the art convinced me that known processes for producing nitric acid by interaction of sodium nitrate and niter cake were fundamentally sound, still it is a fact that none of them yields, on a commercial scale, nitric acid in any degree approaching a quantitative yield. Among the defects of known processes may be recited the following: thermal inefficiency; failure to eliminate residual sodium sulfate from the retort; excessive decomposition and only partial elimination of nitric acid and a yield of nitric acid which is far from quantitative and is seriously lacking in purity and uniformity; low capacity per unit of time; and prohibitive labor cost and unkeep charges on the equipment.

I have discovered that all the foregoing defects of the known processes may be remedied by the following means, namely: differential heating of the retort so as to provide a relatively high temperature zone adjacent the end for the discharge of solid or fused material; restraining the tendency of the material to sinter and cling to the walls of the retort; scraping from the walls of the retort any adhering sodium sulfate, breaking up lumps and preventing the consolidation of material as it fuses; and applying a degree of suction to the retort while restraining free admission of air at the discharge end.

While the execution of the process is not dependent upon the use of any particular apparatus, I prefer to employ the apparatus shown in the accompanying drawings, which has been constructed on a full sized scale, practically operated and tested and demonstrated to be adapted to successfully carry out the process and produce so large a yield

of nitric acid as to be commercially practicable.

In the drawings:

Figure 1 is a sectional view of the furnace for driving off the nitric acid from the mixture.

Fig. 2 is a section through the retort of Fig. 1.

Fig. 3 is an elevation of the condensation and absorption apparatus.

The retort comprises a long rotatable iron cylinder *a* inclined about one-half inch to the foot and turning at opposite ends in machined, air-tight bearings *b* and *c*. The lower bearing *c* is of hollow T-shape, and affords a passage from the retort *a* to the bin *d*. Hollow bearing *c* is provided with an air admission pipe controlled by a valve *z*.

The retort is inclosed in a long, narrow brick furnace *e*. The end of the furnace adjoining the lower end of the retort is provided with a fire-box *f*. Between the fire-box and the other end of the furnace is a bed of cinders *g*. The products of combustion pass up around and thence along the retort and escape by the stack *h*. Outside the end of the furnace adjacent the higher end of the retort is erected a frame *i* carrying driving mechanism *j* by which the driving power is transmitted from a motor to a sprocket wheel *k* secured to the higher end of the retort. The retort at opposite ends rests on rollers *n*, *o*, turning in bearings on the frame *i* and on the frame for the bin *d*.

Extending through the end closure *b* is a feed tube *p* containing a power driven feed screw *r* and communicating with a hopper *s*.

Also extending through the end closure *b* is a tube *t* connected to a pipe *v* which communicates, by a swiveled connection, with the admission pipe of a condensing and absorption system. *x* represents the condenser and *y* the absorption apparatus. These *per se* are of standard construction and therefore need not be described in detail.

The charge, which is placed in the hopper and fed continuously into the retort, consists of a mixture of pulverized niter cake and sodium nitrate, preferably ground

separately, to which is also preferably added ground sodium sulfate or other material to prevent the mixture from sintering and to give a friable residue which will not 5 cling to the retort. The construction and arrangement of the furnace and retort are such that the retort is heated unequally, the zone of highest heat being at the lower end of the retort, the temperature gradually diminishing toward the higher end of the retort. Hence the charge is subjected to a gradually increasing temperature as it moves progressively through the retort. The charging end of the retort is therefore relatively 10 cool. The arrangement permits of a gradual evolution of nitric acid at such a low temperature that minimum decomposition of nitric acid occurs. As the charge approaches the lower or discharge end, it reaches the 15 zone of maximum temperature, wherein complete elimination of nitric acid is effected. Thus, when a temperature promotive of decomposition is reached, the nitric acid has been already largely eliminated; and, further, the charge is within the zone of highest 20 temperature during only a relatively short interval of time. The results are: (1) maximum heat efficiency; (2) maximum production of nitric acid; (3) minimum decomposition 25 of nitric acid; (4) production of high grade sodium sulfate.

So far as described, the mechanical difficulties of carrying out the process are only partly overcome, because, as the mixture is 30 fed into the retort, it melts into a viscous mass which hardens as the nitric acid is driven off, forming normal sodium sulfate with a high melting point, the fused mixture having an extreme tendency to harden to 35 the walls of the retort. Mere agitation and stirring or hammering on the outside walls of the retort do not suffice to prevent this adhesion. I have found, however, that if, during the process, the walls of the retort 40 are scraped free from adhering sodium sulfate and the lumps broken up, nitric acid will be thoroughly eliminated and the residual sodium sulfate pulverized. To effect this operation I prefer to use a steel rail 45 (shown at *w*), a double T-iron, or any other sharp-edged, heavy iron bar, which is laid loosely inside and lengthwise of the retort so as to be free to tumble about as the retort revolves.

50 55 The nitric acid, as produced in the retort, escapes by way of tube *t* and pipe *v* to the condensation and absorption apparatus (*x, y*).

It is preferred to connect the last absorption tower of the series with a pipe in which a slight vacuum is maintained, which is effective throughout the entire apparatus and causes a slow flow of air through the retort to oxidize the lower oxids of nitrogen and

assist in sweeping the nitric acid out of the 65 retort. For this reason the closure at the discharge end of the retort should be airtight, or nearly so, as hereinbefore described. Free admission of air at the discharge end of the retort should be avoided. 70

I do not herein claim the apparatus shown and described for carrying out my process, as the same forms the subject-matter of a separate application filed August 22, 1918, Serial No. 250,978, of which this application 75 is a division.

Having now fully described my invention, what I claim and desire to protect by Letters Patent is:

1. The process of producing nitric acid 80 and sodium sulfate from a mixture of pulverized niter cake and sodium nitrate which comprises imparting to a stream of the mixture a combined tumbling and steadily progressive movement and replenishing the stream at one end and discharging it at the other end, differentially heating the stream by creating a zone of relatively high temperature toward the discharge end and a zone of relatively low temperature toward the supply end, and causing the nitric acid evolved to flow in a direction opposite to the travel of the stream. 90

2. The process of producing nitric acid 95 and sodium sulfate from a mixture of pulverized niter cake and sodium nitrate which comprises imparting to the stream of the mixture a combined tumbling and steadily progressive movement and subjecting the mixture as it advances to a gradually increasing temperature. 100

3. The process of producing nitric acid and sodium sulfate from a mixture of pulverized niter cake and sodium nitrate which comprises imparting to the stream of the mixture a progressive movement, differentially heating the stream by creating a zone of maximum temperature toward the discharge end of the stream, and during the application of heat preventing the consolidation 105 of material as it fuses, breaking up the lumps, and pulverizing the sodium sulfate resulting from the elimination of nitric acid. 110

4. The process of producing nitric acid 115 and sodium sulfate from a mixture of pulverized niter cake and sodium nitrate which comprises imparting to a stream of the mixture a combined tumbling and steadily progressive movement, replenishing the stream 120 at one end and discharging it at the other end, and during said operation scraping the fused material from the inner wall of the retort.

5. The process of producing nitric acid 125 and sodium sulfate from a mixture of pulverized niter cake and sodium nitrate which comprises imparting to an inclosed stream

of the mixture a combined tumbling and steadily progressive movement and continually replenishing the stream at one end and discharging it at the other end, differentially heating the stream by creating a zone of relatively high temperature toward the discharge end and a zone of relatively low temperature toward the supply end, creating a suction to cause a slow flow of air in a direction opposite to the flow of

the solids, thereby oxidizing the lower oxids of nitrogen and assisting the flow of nitric acid in the direction of suction, and restraining the free admission of air to the discharge end of the stream of solids.

15

In testimony of which invention, I have hereunto set my hand, at Kenvil, N. J., on this 7th day of March, 1919.

THOMAS F. BANIGAN.
